(57) **CLAIM**

The ornamental design for a pair of shoe soles, as shown and described.

DESCRIPTION

FIG. 1 is a bottom view of the right component of a pair of shoe soles showing my new design;

FIG. 2 is a bottom view of an alternate embodiment of the design shown in FIG. 1;

FIG. 3 is a 2nd embodiment of the design shown in FIG. 1; and,FIG. 4 is a 3rd embodiment of the design shown in FIG. 1.

The broken lines immediately adjacent to the shaded areas throughout the views define the boundaries of the claim. The broken lines showing the remainder of the sole represent the portion of the design that forms no part of the claim. Neither the lines themselves, nor the areas within them form any part of the claim.
